CLAIM

The ornamental design for a handheld inspection device, as shown and described.

DESCRIPTION

FIG. 1 is a front-right-top perspective view of a handheld inspection device embodying the new design;

FIG. 2 is a front-left-bottom perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof; and,

FIG. 8 is a bottom plan view thereof.

The broken lines in the figures are shown for the purpose of illustrating portions of the handheld inspection device and/or environmental matter and form no part of the claimed

(Continued)

design. The dot-dash broken lines define the bounds of the claimed design and form no part thereof.
